[57] CLAIM

The ornamental design for a holder for pens, pencils and the like, as shown and described.

DESCRIPTION

FIG. 1 is perspective view of a holder for pencils, pens and the like showing my new design;

FIG. 2 is a front elevational view;

FIG. 3 is a bottom plan view, partly broken away;

FIG. 4 is a rear elevational view;

FIG. 5 is top plan view;

FIG. 6 is a right side elevational view, the left side being the mirror image thereof;

FIG. 7 is a view in section taken along lines 7—7 in FIG. 3;

FIG. 8 is a perspective view of a modified embodiment of the design shown in FIGS. 1 through 7;

FIG. 9 is a front elevational view;

FIG. 10 is bottom plan view, partly broken away;

FIG. 11 is a rear elevational view;

FIG. 12 is top plan view;

FIG. 13 is a right side elevational view, the left side being the mirror image thereof;

FIG. 14 is a view in section taken along lines 14—14 in FIG. 10;

FIG. 15 is a perspective view of a second modified embodiment of the design shown in FIGS. 1 through 7;

FIG. 16 is a front elevational view;

FIG. 17 is a bottom plan view, partly broken away;

FIG. 18 is a rear elevational view;

FIG. 19 is top plan view;

FIG. 20 is a right side elevational view, the left side being the mirror image thereof;

FIG. 21 is a view in section taken along lines 21—21 in FIG. 17;

FIG. 22 is a perspective view of a third modified embodiment of the design shown in FIGS. 1 through 7;

FIG. 23 is a front elevational view;

FIG. 24 is bottom plan view, partly broken away;

FIG. 25 is a rear elevational view;

FIG. 26 is top plan view;

FIG. 27 is a right side elevational view, the left side being the mirror image thereof;

FIG. 28 is a view in section taken along lines 27—27 in FIG. 24;

FIG. 29 is a perspective view of a fourth modified embodiment of the design shown in FIGS. 1 through 7;

FIG. 30 is a front elevational view;

FIG. 31 is bottom plan view, partly broken away;

FIG. 32 is rear elevational view;

FIG. 33 is top plan view;

FIG. 34 is a right side elevational view, the left side being the mirror image thereof;

FIG. 35 is a view in section taken along lines 35—35 in FIG. 31;

FIG. 36 is a perspective view of a fifth modified embodiment of the design shown in FIGS. 1 through 7;

FIG. 37 is a front elevational view;

FIG. 38 is bottom plan view, partly broken away;

FIG. 39 is a rear elevational view;

FIG. 40 is top plan view;

FIG. 41 is a right side elevational view, the left side being the mirror image thereof;

FIG. 42 is a view in section taken along lines 42—42 in FIG. 38.
